UNITED STATES PATENT OFFICE

FRANCIS E. QUEST, OF KNOXVILLE, PENNSYLVANIA, ASSIGNOR OF ONE-HALF TO OTIS H. QUEST, OF KNOXVILLE, PENNSYLVANIA

SMOKING DEVICE

Application filed January 10, 1927. Serial No. 160,045.

This invention relates to smoking devices and more particularly to an improved arrangement for use with pipes, cigarette holders and the like for the purpose of cooling the smoke and extracting the nicotine and heavy oils therefrom.

Various arrangements for accomplishing this purpose have hitherto been employed, but these have generally been so constructed as to be difficult, if not impossible, to properly clean, with the result that they not only eventually become useless through lack of cleaning but constitute in themselves sources of trouble.

An object of this invention is to provide a device of the type set forth of such construction and arrangement as to effectively remove the nicotine and the like from the smoke and which can at the same time be readily cleaned.

A further object is to construct a pipe of such construction and arrangement that any clogging of the smoke passage leading from the bowl thereof can be easily and quickly overcome.

A still further object is to provide a device of the type set forth which will be of simple construction, cheap to manufacture and positive and reliable in operation.

These and other objects which will be apparent to those skilled in this particular art are accomplished by means of the invention illustrated in the accompanying drawing, in which Figure 1 is a longitudinal sectional view through a pipe constructed in accordance with one embodiment of this invention. Fig. 2 is a similar view of a cigarette holder, showing an additional detail for use with this class of article and Fig. 3 is a section on the line 3—3 of Fig. 1.

The particular embodiment of the present invention which has been chosen for the purposes of illustration is shown in connection with a pipe stem 5 having the usual mouthpiece or bit 6 associated therewith and provided with a bowl 7. A nicotine collector 8 is provided and, as illustrated, the collector is secured to the mouthpiece 6 in the usual manner. The collector extends throughout the length of the pipe stem and is provided

with alternately arranged, crosswise extending flattened portions 9 and 10 formed so as to provide outwardly projecting lugs 9' and 10' having hollowed or concave sides 9'' and 10'', respectively. Such a form of collector provides a circuitous passageway 11 or irregular or varying cross section from the bowl to the mouthpiece. It will be apparent that the passageways on each side of the lugs 9, for example, between the crosswise extending portions 10 is of substantial area while the opening between each pair of crosswise extending flattened portions, indicated at 13, is of relatively small size. The shoulders 14 formed around the openings 13 of reduced area provide obstructions on which the nicotine and the like is collected and from which it cannot be drawn through the stem to the mouthpiece, so that the latter is kept free of the unpleasant liquids which so frequently pass through a pipe. The mouthpiece is provided with the usual bore 15 communicating with a similar bore 16 in the cooperating end of the collector 8. A cross bore 17 is provided for connecting the bore of the mouthpiece with the passageway 11. The end of the collector has a circular projection 18 in the form of a cylindrical cup or the like which is normally positioned beyond the passageway 19 leading from the pipe stem to the bowl 7. Preferably the cup or circular end 18 of the nicotine collector fits snugly within the pipe stem 5 so that as it is withdrawn therefrom it serves to effectively scrape and clean the same and remove the collected material from the stem. It will be apparent that the collector constructed as described can be easily and quickly cleaned, particularly if a small brush is used for the purpose. If made from heat absorbing material such, for example, as aluminum or the like it will also tend to cool the smoke.

In Fig. 2 the collector is shown in use with a cigarette tube or holder 20 and is similar in all respects to the smoke cleaner or collector illustrated in Fig. 1, except that the cylindrical cup at the end of the collector used with a pipe is omitted. Preferably a pointed finger 21 or the like is provided on the end of the collector 8 in the cigarette tube and is off-

set laterally from the axis of the associated collector. Such an arrangement securely holds the cigarette within the tube and can also be used as an ejector by withdrawing 5 the collector sufficiently to remove the finger 21 from the cigarette and then returning it to its original position so that the end of the cigarette is forced out of the tube. By offsetting the ejector finger laterally from the 10 axis of the cigar or cigarette holder it can be rotated relatively to the cigar or cigarette end so that it will positively eject the latter and not merely re-enter the hole previously made by it in the cigar or cigarette.

15 The present invention also contemplates the provision of mechanism for preventing or overcoming the stopping of the smoke passage in the pipe leading from the bowl to the stem by particles of tobacco. As illustrated, this is accomplished by extending the 20 shaft 22 having the passageway 19 into the interior of the bowl and providing it with an inclined end 23. The pipe bowl 7, as illustrated, is rotatably supported upon the suitable shaft 22, and it will be apparent that 25 rotating the bowl will cause any tobacco particles to be dragged from the end of the passageway 19 by the movement of the surrounding tobacco across the inclined face on the 30 end of the shaft.

What I claim as new and desire to secure by Letters Patent is:

1. A pipe having in combination a stem, a hollow shaft leading therefrom and a bowl 35 movably mounted on said shaft, the end of said shaft being inclined so that movement of said bowl relatively thereto will prevent particles of tobacco from clogging the opening thereof.

40 2. The combination in a smoking device having a hollow stem, of a nicotine collector 45 located in said stem and having crosswise extending flattened portions forming oppositely extending lugs, each portion being arranged at right angles to the adjacent portion so that the edges of said lugs form nicotine 50 collecting shoulders around relatively offset smoke passing openings.

3. The combination in a smoking device 55 having a hollow stem, of a nicotine collector located in said stem and having crosswise extending flattened portions forming oppositely extending lugs, each portion being arranged at right angles to the adjacent portion 60 so that the edges of said lugs form nicotine collecting shoulders around relatively offset smoke passing openings and a cylindrical end engaging the inner wall of said stem so as to scrape and clean the same when 65 said collector is withdrawn therefrom.

4. A pipe of the character described having 70 in combination a stem, a hollow shaft having an inclined end leading from said stem, a bowl movably mounted on said shaft 75 and a nicotine collector fitting in said stem,

said collector having a series of flattened portions arranged oppositely to each other forming a relatively offset smoke passage and having a cylindrical end engaging the inner wall of said stem for scraping and cleaning the stem when the collector is withdrawn 70 therefrom.

In testimony whereof, I have hereunto subscribed my name this 7th day of January, 1927.
